UNITED STATES PATENT OFFICE.

ROBERT B. MITCHELL, OF NEW ORLEANS, LOUISIANA.

CROZING-MACHINE.

SPECIFICATION forming part of Letters Patent No. 241,232, dated May 10, 1881.

Application filed June 19, 1880. (No model.)

To all whom it may concern:

Be it known that I, ROBERT B. MITCHELL, a resident of the city of New Orleans, parish of Orleans, and State of Louisiana, have invented a certain new and useful Improvement 5 in Crozing-Machines; and I do hereby declare the following to be a full, clear, and correct description of the same, reference being had to the annexed drawings, making a part of this 10 specification.

This invention is especially intended for use in the manufacture of cisterns, tanks, barrels, buckets, &c., inasmuch as it enables an operator to accomplish a greater amount of work 15 within a given time and in a much better and more satisfactory manner than if done by hand, as heretofore. In addition to its being used as a crozing-machine, it can be readily arranged to square or trim off the ends of the staves.

20 The construction and operation of this machine will be readily understood by referring to the accompanying drawings, in which—

Figure 1 represents a perspective view thereof, and Fig. 2 a vertical cross-section through 25 the line $x x'$.

On the drawings, aa' represent the side pieces of a frame, that are supported on suitable legs, as shown at bb' . This frame is furnished with journal-boxes $c c'$, in which is operated a shaft, 30 d , that is provided at one end with a pulley, f , and at the other (inner end) with a cutter-head or crozing-tool, g , of any desired construction.

Between the side pieces of the frame is a cross-tie, h , on the upper surface of which is fitted a sliding gage, i , whereby the distance 35 between the crozing and end of stave is regulated.

Pivoted to the inner side of the above-mentioned frame is an arm, k , the rear end of which 40 is bent downward and slotted, so as to receive a screw, l , whereby it is securely held in any desired position. The inner end of this arm projects over the cutter-head, and this end is provided with a friction-roller, as shown at m .

45 A second frame, also composed of two parallel side pieces, $n n'$, supported on legs $o o'$, is se-

cured at right angles to the inner piece of the first frame, as clearly shown in Fig. 1. On a central line the lower portions of the legs $o o'$ are provided with vertical slots, in which are fitted wrists $r r'$. These are held at any desired height by the tightening of nuts that are fitted to threaded portions of the same. To these wrists are fitted the lower ends of vibrating arms $S S'$, the upper portions of which are connected with and serve as supports for the stave-rest t .

In order that the stave to be operated upon may be kept in contact with the friction-rollers m , that wrist which is nearest the cutter-head is connected by a link, u , with the inner end of a beam, v , the latter pivoted to the supporting-leg o , and having the upper surface of its outer end notched, as shown, to receive a weight, w , which is so adjusted as to little more 65 than counterbalance the weight of the stave and stave-rest, thus holding the work close against the roller m without producing any unnecessary friction.

I claim as my invention—

1. In combination with a crozing-tool, the stave-rest t , link u , beam v , and weight for feeding the material to the crozing-tool and counterbalancing the weight of the material, substantially as and for the purpose set forth. 75

2. In combination with a crozing-tool, the gage i , stave-rest t , and friction-roller m , all operating in the manner substantially as and for the purposes set forth.

3. In combination with a crozing-tool, the arm k , pivoted at or near its rear end and provided with a slot for adjustment, and having at its upper or forward end a roller arranged over the crozing-tool, substantially as and for the purpose set forth. 85

In testimony whereof I have hereunto signed my name.

ROBT. B. MITCHELL.

In presence of—

JAMES C. KIDDELL,
PETER J. FINNEY.
